DESIGN FOR A RUNNER FOR A VACUUM CLEANER OR SIMILAR ARTICLE

Gustaf Einar Lofgren, Riverside, Conn., assignor
to Electrolux Corporation, Dover, Del., a cor-
poration of Delaware

Application September 8, 1937, Serial No. 71,511

Term of patent 14 years

To all whom it may concern:

Be it known that I, Gustaf Einar Lofgren, a
subject of the King of Sweden, residing in River-
side, Connecticut, have invented a new, original,
and ornamental Design for a Runner for a Vac-
uum Cleaner or Similar Article, of which the
following is a specification, reference being had
to the accompanying drawing, forming part
thereof.

Fig. 1 is a side view of my new design of
runner.

Fig. 2 is a perspective view of the runner, and
Fig. 3 is a sectional view, along line 3—3 of
Fig. 1.

I claim:

The ornamental design for a runner for a
vacuum cleaner or similar article, as shown.

GUSTAF EINAR LOFGREN.
